[57] CLAIM

The ornamental design for a vending machine front panel assembly, as shown.

DESCRIPTION

FIG. 1 is a front perspective view of a vending machine front panel assembly showing my new design;
FIG. 2 is a front elevational view thereof;
FIG. 3 is a cross sectional view thereof taken on line 3—3 of FIG. 2;
FIG. 4 is a rear elevational view thereof; and
FIG. 5 is a front elevational view of a second embodiment of a vending machine front panel assembly showing my new design.
